Primary Examiner — Ryan Harvey(74) *Attorney, Agent, or Firm* — Nexsen Preut, PLLC; E. Eric Mills(57) **CLAIM**

The ornamental design for a fitness tower, as shown and described.

DESCRIPTION

FIG. 1 is a perspective view of a fitness tower showing a new design;

FIG. 2 is a top view thereof;

FIG. 3 is a left side view thereof;

FIG. 4 is a right side view thereof;

FIG. 5 is a front view thereof; and,

FIG. 6 is a bottom view thereof.

The broken lines illustrate portions of the article that form no part of the claimed design.

1 Claim, 6 Drawing Sheets(56)
